UNITED STATES PATENT OFFICE

GEORGE W. ELSEY, OF ANDERSON, INDIANA, ASSIGNOR TO DELCO-REMY CORPORATION, OF DAYTON, OHIO, A CORPORATION OF DELAWARE

STRAP END ATTACHMENT

Application filed May 10, 1928. Serial No. 276,693.

This invention relates to improvements in strap end attachments.

It is among the objects of the present invention to provide a simple and inexpensive anchoring means for a flexible member, by means of which the flexible member may be anchored to another part with a minimum of time and labor.

Further objects and advantages of the present invention will be apparent from the following description, reference being had to the accompanying drawings, wherein a preferred form of embodiment of the present invention is clearly shown.

15 In the drawings:

Fig. 1 illustrates the device anchoring the flexible strap of a shock absorber to the spring of a vehicle.

Fig. 2 is a fragmentary sectional view of a loop-forming member attached to the end of a strap.

Fig. 3 illustrates the blank from which the loop-forming member is formed.

Fig. 4 is a side view of the loop-forming member.

Fig. 5 is an elevational view of the loop-forming member.

The first step in producing the loop-forming member illustrated in the Fig. 4 of the drawing is to cut a blank as designated by the numeral 20 shown in the Fig. 3. Serrations 21 are necessarily provided at one end of the blank for purposes to be described. The serrations 21^a at the other end of the blank are not necessary in the application of the loop-forming device to a strap, however, these serrations 21^a result from a single cut across the strip of stock metal inasmuch as such a single cut substantially reduces the waste of the metal in the production of this device.

After the blank has been cut, the one end of said blank is bent as shown at 22 to form the spreader end as shown in the Figs. 2 and 4. The other end of the blank is hook-shaped as shown at 23, the free branch 24 of said hook-shaped end being spaced from the main body 25 of the structure. One end 26 of a flexible strap 27 is placed in the space between the branch 24 and body 25 of the

structure and then said branch and body are pressed together causing the serrations 21 to bite into the flexible strap end 26 securely to clamp the end 26 of the strap between them. The strap, as shown in Fig. 2, is then 55 bent about the spreader portion 22 of the metallic structure thereby providing a loop or enlarged end portion on the strap.

The device is shown in the present drawings as used in connection with a shock absorber. The vehicle spring 30 has a bracket 31 secured thereto by a stud 32. The bracket has an aperture 33, presenting two converging walls. The arm 34 is the operating member of the shock absorber 35 which is 60 attached to the frame 36 of the vehicle in any suitable manner. The flexible strap 27 is inserted and drawn through the aperture 33 of bracket 31 so that the enlarged end will enter and wedge itself into said aperture, 65 as shown in Fig. 1. The other end of the strap 27 is secured to the shock absorber arm 34 by a stud 37. Means within the shock absorber tend to operate the arm 34 constantly to hold the strap 27 taut and 70 thereby maintaining the enlarged end of the strap in its wedging relation with the aperture 33.

The present structure provides a metallic member of simple structure and design, 80 which may be produced at a minimum expense of time and labor and which may also be attached to the end of the flexible strap in a comparatively short time, thereby substantially facilitating the production of this 85 portion of a shock absorber installation.

While the form of embodiment of the present invention as herein disclosed, constitutes a preferred form, it is to be understood that other forms might be adopted, all coming 90 within the scope of the claims which follow.

What is claimed is as follows:

1. A device of the character described comprising a member having a looped and a hook-shaped end, the first of which provides 95 a spreader portion about which a flexible part is wound, the other being open for receiving the end of a flexible part upon which said hook end is pressed firmly to clamp the flexible part to the member.

2. A device of the character described comprising a metallic member having one loop end and the other hook shaped, serrations on the hook-shaped end, a flexible strap, one end of which fits into the hook-shaped end of the metallic member, the serrations of which bite into and firmly secure the member upon the strap when said hook-shaped end is pressed together, so as to clamp the strap therein, the loop end providing a core about which the flexible strap is wound to provide a loop therein.
3. A strap-anchoring device comprising an anchoring member having an aperture presenting a pair of converging walls, a strap having a spreader permanently connected thereto, whereby said strap is firmly wedged between said walls when inserted into said aperture, said spreader comprising a member having a hook end and a spreader end, the hook end being adapted to be pressed together to have the strap end clamped therebetween thus firmly securing said member to the strap end, the spreader end having the strap bent about it to provide an enlarged end on the strap adapted to be wedged into the aperture of the anchoring member.
4. A loop-forming device for a flexible instrumentality comprising, a member having a hook end providing a bight for receiving one end of the flexible instrumentality, means adapted to be embedded in the said flexible instrumentality for securely attaching the said member thereto, and a loop end on said member providing a core about which said instrumentality is wrapped to form a loop therein.

In testimony whereof I hereto affix my signature.
